Stephen Stucky
By Alexander Mason
att,

UNITED STATES PATENT OFFICE.

STEPHEN STUCKY, OF LINCOLN, ALABAMA.

BALE-BAND TIGHTENER.

SPECIFICATION forming part of Letters Patent No. 284,734, dated November 23, 1880.

Application filed April 27, 1880. (No model.)

To all whom it may concern:

Be it known that I, STEPHEN STUCKY, of Lincoln, in the county of Talladega, and in the State of Alabama, have invented certain new and useful Improvements in Bale-Band Tighteners; and I do hereby declare that the following is a full, clear, and exact description thereof, reference being had to the accompanying drawings, and to the letters of reference 10 marked thereon, making a part of this specification.

The nature of my invention consists in the construction and arrangement of a device for tightening the bands on cotton-bales, as will 15 be hereinafter more fully set forth.

In order to enable others skilled in the art to which my invention appertains to make and use the same, I will now proceed to describe its construction and operation, referring to 20 the annexed drawings, in which—

Figure 1 is a side view of a cotton-bale and band, with my tightener in position. Fig. 2 is an end view thereof. Fig. 3 is a plan view of the tightener. Figs. 4, 5, 6, and 7 are 25 drawings, in which—

A represents a straight bar of any suitable dimensions, over each end of which is passed a bridle, B, of strap-iron. The strap-iron is doubled over the end of the bar and riveted 30 thereto, and then the doubled iron extended down to a lever, C, to which both bridles are fastened by a bolt, a.

Near the center of the bar A is riveted or otherwise fastened a metal tongue or gripe, D, 35 the inner end of which is beveled, as shown at b, for the easy insertion of the bale-band. Corresponding with this tongue or gripe is an oval button, F, the shank of which passes through the bar A, and has upon its end a handle, I, 40 for turning the button. The under side of the button is beveled like the tongue or gripe.

To use this band-puller, the button F is first turned across the bar and the end of the bale-band at the top of the bale inserted under the 45 tongue or gripe D. The button F is then turned by means of its handle so as to come over the band, which is then griped or held firmly by said tongue and button. The end of the lever C is then inserted in the groove in the lower 50 platen of the press under the lower end of the

bale-band. By now pressing down on the lever the lower end of the bale-band is held tightly while the upper end is drawn downward, leaving the two extreme ends of the band perfectly loose and free, so that the operator can 55 throw his leg over the lever and hold the same down, and has use of both hands to fasten the buckle. With this device the band can be so tightened that when the buckle is fastened and the bale removed from the press there will 60 be but very little expansion of the bale.

As a modification I may make the button F in the form shown in Figs. 4 and 6, and provide the same with an eccentric, d, which, when the button is turned over the band, will 65 press the band tightly under the tongue or gripe D. The tongue and button meeting in the center of the band will prevent the same from buckling.

By attaching the gripping devices to a long 70 bar, A, and connecting the ends of this bar by bridles to a lever, as described, there is always an open space left in which the ends of the bale-band can be manipulated for fastening the buckle without inconvenience from any 75 part of the device itself.

The inner end of the lever C is preferably made in the claw shape, as shown in Fig. 7, which will admit of the device being used on bales that have already been tied for the purpose of removing the buckles without destroying 80 the band, as the device may be applied in the same manner as above described, and will then hold and press together both ends of the band so as to render the extreme ends, where 85 the buckle is fastened, free and loose, and thereby enable the operator to detach the buckle from the band without cutting.

Having thus fully described my invention, what I claim as new, and desire to secure by 90 Letters Patent, is—

1. A cotton-band puller or tightener, consisting of a lever, C, bridles B B, and a bar, A, provided with gripes for holding one end of the band, substantially as herein set forth. 95

2. The combination of the bar A, tongue or gripe D, pivoted button F, with or without an eccentric, the bridles B B, and lever C, all constructed substantially as and for the purposes herein set forth. 100

3. In a bale-band tightener, a long bar, A, provided in the center with suitable gripping devices, and its ends connected to a single operating-lever, substantially as described, where-
5 by an open space is left in the center for the tying of the buckle, substantially as herein set forth.

In testimony that I claim the foregoing I have hereunto set my hand this 26th day of April, 1880.

STEPHEN STUCKY.
